UNITED STATES PATENT OFFICE.

HOMER CLYDE SNOOK, OF PHILADELPHIA, PENNSYLVANIA.

X-RAY SYSTEM.

1,233,137.

Application filed April 13, 1909, Serial No. 489,551. Renewed November 9, 1916. Serial No. 130,476.

To all whom it may concern:

Be it known that I, HOMER CLYDE SNOOK, a citizen of the United States, residing in the city of Philadelphia, county of Philadelphia, and State of Pennsylvania, have invented a certain new and useful Improvement in X-Ray Systems, of which the following is a specification.

My invention relates to a system and apparatus for delivering high potential unidirectional current to an X-ray tube or other translating device, or to a consumption circuit.

My invention resides in a system and apparatus involving and carrying forward the principles described and claimed in my Letters Patent of the United States No. 954,056 and No. 1,131,870.

My invention resides in a system and apparatus involving a switch for rectifying high potential alternating currents for general use, and particularly for the excitation of X-ray tubes, whereby substantially all or any desired smaller part of each half current wave in a single phase system or a large or other suitable fraction of each half wave in a polyphase system is delivered to the X-ray tube or other translating device or circuit, and all of the half waves delivered in the same direction. And in my system and apparatus the high potential rectifying switch is of small dimensions considering the potentials involved and its relatively moving contacts are submerged in a medium having far greater dielectric strength than air, such as oil, a compressed air or other gas, etc.

My invention resides in an X-ray system in which the resistance of the X-ray tube circuit is maintained substantially constant and is devoid of resistance pulsations such as have been caused in prior systems by air gaps varying in length; and my invention resides in an X-ray system in which connection from the X-ray tube to the means delivering high potential impulses is through a rectifying switch and a path of unvarying resistance, the resistance through and between the co-operating rectifying switch contacts being practically constant for all relative positions of those contacts.

My system herein described is similar to the polyphase system described in my aforesaid Patent No. 1,131,870, in that the high potential energy of polyphase current is transmitted as uni-directional uninterrupted

ed high potential energy to the consumption or work circuit. And in my present system the advantages as to X-ray tubes are similar to those of the system of my said prior application, in that the digging or pitting of the target or anti-cathode, with a given mean energy, is reduced, fluctuation in vacuum is also reduced and greater uniformity of rays procured.

In the system herein described, however, there is a further advantage, in that fluctuations in resistance in the consumption or work circuit are substantially suppressed, because in the switching apparatus actual engagement takes place between the relatively moving contacts, air gaps being avoided, as above described.

I accordingly believe myself to be the first to deliver to a work or consumption circuit uni-directional high tension current, that is, current at voltages higher than five thousand or ten thousand volts upward to more than one hundred thousand volts, without substantial fluctuation of resistance of the consumption circuit, particularly when the consumption circuit contains a vacuum or X-ray tube, and when the energy delivered to the switching mechanism is either single or polyphase current, and when polyphase current, causing delivery of uninterrupted uni-directional current to the consumption circuit.

My invention resides also in other features hereinafter described and claimed.

For an illustration of some of the forms my invention may take, reference is to be had to the accompanying drawings, in which:

Figure 1 is a diagrammatic view illustrating the apparatus and circuit arrangements of my system involving a rectifying switch such as shown in Figs. 3 and 4.

Fig. 2 is a diagrammatic view illustrating my apparatus and system involving a modified form of rectifying switch, such, for example, as shown in Fig. 5.

Fig. 3 is a vertical elevational view, partly in section, of one form of my high potential rectifying switch mechanically connected with the rotating member of the producer of the fluctuating or alternating current.

Fig. 4 is a horizontal sectional view, partly in plan, taken on the line 2--2, Fig. 3, and looking in the direction of the arrows.

Fig. 5 is a fragmentary view of a modi-

fied form of rectifying switch, parts being shown in section.

Fig. 6 is a graphic representation of the uni-directional current waves and their resultant.

- Referring to Fig. 1, L and L¹ are the conductors of an electric supply circuit leading to the motor side M of a motor generator or inverted rotary R, whose generator side G 10 delivers three phase alternating current to the three conductors 1, 2, and 3 through the adjustable resistances 4, preferably non-inductive, to the primaries p¹, p², and p³ of the three phase transformer T having the high 15 potential secondaries s¹, s², and s³, here shown as Y connected and having their common terminal connected to earth 6 by conductor 5. The three transformer secondaries have their other terminals connected through the 20 high frequency choke coils D with the brushes 7, 8, and 9 which bear respectively upon the three slip rings 10, 11, and 12 of the high potential rectifying switch E such as shown in Figs. 3 and 4. The slip ring 25 10 connects by conductor 13 with the conducting arcs 14; the slip ring 11 connects by conductor 15 with the conducting arcs 16; and the slip ring 12 connects by conductor 17 with the conducting arcs 18.
- 30 In the arrangement shown, a pair of roller brushes 19, 19^a is disposed substantially at right angles to a similar pair of brushes 20, 20^a. The distance between the points of contact of the roller brushes of each pair is substantially equal to the width of the insulation 21, between neighboring conducting segments or arcs 14, 16, 18, and should preferably be not greater than the width of the insulation 21. And it is desirable that 35 the width of the insulation 21 between conducting arcs or segments should not be greater than the circumferential width or angular extent of the conducting arcs or segments themselves. And the roller brushes 40 of each pair are not in direct electrical communication with each other but are connected by a high inductive or high non-inductive resistance 22. The resistance 22 serves to minimize current flow between the 45 two brushes to which it is connected during the time that those brushes are in contact with different conducting arcs or segments. And from points at substantially the middle of the high inductances or non-inductive resistances 22 extend the conductors 23 and 24 to the two terminals of an X-ray tube or other translating device X, an ammeter F, if desired, intervening in one of these conductors as 24.
- 50 In the system just described stationary windings in which polyphase E. M. F.'s are induced or developed are connected to rotating contact segments or arcs through the medium of slip rings, and a pair of collectors co-operates with the contact segments 55

or arcs to take off unidirectional current. Here one mechanical cycle of the rectifying switch E corresponds with two electrical cycles.

The apparatus may also be arranged with 70 connections from the stationary windings to stationary contact arcs or segments the brushes or collectors then becoming the rotating members.

And, if four collectors be used instead of 75 two as shown, and three neighboring arcs connected to three slip rings, the cross connections between the conducting arcs or segments need not be used with two electrical cycles to one mechanical cycle, opposing 80 pairs of collectors being in such case connected together.

The rotating element of the rectifying switch E is driven in synchronism with the current which it rectifies, and by preference 85 by a mechanical connection with the rotating member of the source or generator G which delivers the alternating current to the transformer T, which preferably has very small magnetic leakage.

90 The switch E rectifies the current in each of the three phases so that there are in effect overlapping half waves in the consumption circuit. These overlapping half waves then cause in the circuit of the tube 95 X unidirectional impulses of a frequency triple the frequency of one-half cycle supplied by the transformer T. And this triple frequency current has a potential or voltage which is higher than the voltage of any one 100 of the secondaries s¹, s², or s³.

While the arcs or segments 14, 16 and 18 may be less than 60 mechanical degrees or 120 electrical degrees in extent, yet the period of contact with each arc or segment, 105 because each pair of brushes constitutes separate contacts connected through a high inductance or high resistance, is substantially equal to a time corresponding with 120 electrical degrees.

110 In Fig. 3 is shown the inverted rotary R or a generator G of the current delivered to the transformer T. This generator or converter is supported by the bracket 25 upon the plate or member 26 preferably of insulating material, which is in turn supported on any suitable device or member 27. Extending through a bushing 28 in the member 26 is the shaft 29 upon which is secured the insulating material 30, such as hard rubber. 120 Upon the member 30 are mounted the slip rings 10, 11, and 12 which are connected by conductors 13, 15 and 17, as shown in Fig. 1, (and extending through the mass 30) with the conducting arcs or segments 14, 16 and 18, respectively, which, as before stated, are separated by insulation 21, which may consist of blocks of mica or other suitable material set in between neighboring arcs or segments and secured in the mass 30 of insu- 125 130

lating material. Upon the slip rings 10, 11, and 12 bear the brushes, preferably roller brushes, 7, 8, and 9, as shown, such brushes being supported by the insulating members 5 31 depending from the plate or member 26 and connected at their bottom by a yoke 32 having at its center a bearing 33 for the lower end of the shaft 29. This shaft is directly coupled to the shaft 34 of the generator 10 or converter R, an insulating coupling 35 intervening.

Adapted to contact the conducting arcs or segments 14, 16 and 18 are the pairs of roller contacts 19, 19^a and 20, 20^a each pair 15 being supported upon an insulating member 36 resiliently mounted by a leaf spring 37 upon the support 38 held in position upon the vertical insulating members 31. Springs 39 press inwardly upon the members 36 to 20 cause the roller brushes to maintain physical contact with the conducting segments or arcs 14, 16 and 18 and their intervening insulation 21, the springs 39 bearing at their outer ends against the inner walls of the 25 tank or casing 40 supported by the plate or member 36 and containing oil to a level above all of the slip rings, conducting arcs or segments, and their coöperating brushes or collectors.

30 Or the chamber formed by the tank or enclosure 40 may be air or gas tight and may contain any suitable gas or other material having a greater disruptive voltage than air, air or gas under pressure being available when suitable.

35 By the arrangement shown the system disclosed in Fig. 1 may be used with a high potential rectifying switch occupying a minimum of space or volume and yet operating satisfactorily to rectify the alternating current of high potential, as, for example, from 40 50,000 to 150,000 volts.

In Fig. 2, the primaries of the transformer T and the rotary converter or generator R or G are not shown. The secondaries s^1 , s^2 and s^3 are the same as shown in Fig. 1 and are connected through the high frequency inductances D with roller or other brushes of a rectifying switch H comprising 45 the three disks w^1 , w^2 and w^3 of insulating material capable of withstanding the high potentials involved, there being one of these insulating disks for each phase of the transformer secondary current. The transformer 50 in this case again is preferably of a type having very small magnetic leakage. Set into the insulating disk w^1 is a conducting arc 41 which extends entirely through the disk w^1 and has an exposed face on each 55 side of the disk. On one side of the disk, the front, for example, are arranged the four roller brushes or other contacting devices 42 all electrically connected together and to a terminal of the secondary s^2 . On 60 the other side of the disk, the rear, for ex-

ample, are the two pairs of opposed roller brushes or similar contacting devices, one pair 43, 43 electrically connected to the conductor 23, and a similar pair 44, 44 disposed at right angles to the first pair and both 70 electrically connected to the conductor 24, the conductors 23 and 24 being the consumption circuit including the X-ray tube X, or other suitable translating device, an ammeter F as shown being included in such circuit. 75 The three disks w^1 , w^2 , w^3 are all mechanically connected to and driven by a shaft 29, preferably mechanically connected to the converter or generator R or G such as shown in Figs. 1 and 3.

80 The second disk w^2 has a conducting arc 45 set in, but this arc is in a different angular position with respect to the driving shaft than the arc 41 of the disk w^1 . And with disk w^2 are associated four roller brushes or 85 contacting devices 46 on the front side all connected together and to the terminal of the secondary s^1 . On the rear the opposing pair of similar contacting devices 47 are electrically connected to the conductor 23; 90 while the pair 48 disposed at right angles to the pair 47 are also electrically connected to the conductor 24. And finally, in the case of disk w^3 we have a third conducting arc 49 set in and coöperating with the four 95 roller or other contacting devices 50 on the front side, all connected to a terminal of the secondary s^3 , and the opposed pair 51 on the rear side connected to the conductor 23, and the second pair 52, at right angles, 100 both connected to the conductor 24. As here shown each of the conducting arcs 41, 45 and 49 has an angular or circumferential extent of substantially 60 degrees corresponding with substantially 120 electrical 105 degrees, and each is shifted with respect to the other substantially 60 mechanical degrees or 120 electrical degrees.

110 The disks w^1 , w^2 , w^3 and the associated contacting devices are all preferably submerged in oil, air or gas under pressure, or in any medium having higher insulating power than air.

115 When in operation, the shaft 29, as shown in Fig. 5, is rotated by the shaft of the converter or generator R or G thus carrying the conducting arcs 41, 45 and 49 around in synchronism and thus closing circuit between opposed contacts or rollers and bringing the consumption circuit 23 and 24 into communication with the secondaries of the transformer T in a certain order of succession and at certain relative times so that to said consumption circuit there is delivered high potential unidirectional current.

120 The switch H rectifies the current in each of the three phases so that there are, in effect, in the consumption circuit overlapping half waves. These overlapping half waves then cause in the consumption circuit 130

unidirectional impulses of a frequency triple the frequency of one half cycle supplied by the transformer T. And this triple frequency current has a potential or voltage 5 which is higher than the voltage of any one of the secondaries s^1 , s^2 , or s^3 .

The inserted conducting arcs, as 41, 45, and 49, may be slightly less than 60 mechanical degrees or 120 electrical degrees in extent, 10 but they should be made substantially 60 mechanical degrees or 120 electrical degrees in extent for a three phase system.

As seen from Fig. 6, the hereinbefore described switching mechanisms rectify the 15 current of each phase, so that there are the overlapping half waves a , b , c , a' , b' , and c' , of which a , b and c represent the positive half waves of the three different phases, and a' , b' and c' represent the turned over negative half waves. The switch relations are such that each transformer secondary is in circuit for each half wave for a time corresponding with the length d . There results then in the circuit of the tube X a fluctuating 20 current of frequency triple the frequency of a half cycle of one phase supplied by the transformer T, this triple frequency current being represented by the curve e in the upper part of Fig. 6. This curve is obtained by adding the ordinates of those 25 parts of the curves below for and during such periods as the different phases are actively in circuit as controlled by the switching mechanism. It will be noted that the 30 minimum potential impressed upon the terminals of tube X, represented by the distance f , is greater than the potential of any one of the secondaries of the transformer T. This curve shows that the tube X is 35 constantly subjected to a potential whose minimum is f which is always greater than the potential delivered by any one phase of the transformer T, and this minimum potential f is sufficient to excite the tube X.

40 This minimum potential f occurs at a moment or instant when the secondary delivering the current wave c' is in series with the other two secondaries in parallel with each other. Accordingly, the ordinate f is equal 45 to the sum of the maximum ordinate of curve c' plus the ordinate at the intersection of the half waves a and b directly below the maximum of the curve c' . A maximum of the curve e occurs at the instant corresponding 50 with the intersection of the curves a and c' , and such maximum ordinate of the curve e is equal to twice the ordinate of the intersection of a and c' , because then the two secondaries delivering the current waves a 55 and c' are in series with each other.

60 While I have in the drawings disclosed a three phase system and apparatus, it is to be understood that my system and rectifying apparatus are adaptable also to a single

phase current or to a current of any number 65 of phases.

By the system herein described, I do not employ an air gap in the rectifying switch and do not employ a resistance which is synchronously varied. By my system substantially all of each half of the current waves, in a single phase system, or a large fraction in polyphase systems, of both signs, are impressed upon the consumption circuit, and with small magnetic leakage in the 75 transformer and by a mechanical connection between the rotating member of the rectifying switch and the rotatable member of the current producer, current in inverse direction in the consumption circuit is avoided, 80 and in the case of an X-ray tube circuit, inverse discharge in the tube is prevented, thus resulting in the prevention of reduction of intensity of excitation of the tube and also in the prevention of shortening of life of the 85 tube. And from the fact that the resistance of the tube circuit, exclusive of the tube itself, is constant, as attained by the rectifying switch described, or from the additional fact of the low magnetic leakage of the 90 transformer coöperating with the advantages produced by the rectifying switch, the strength of the current through the X-ray tube varies only with the variation of the 95 resistance of the tube itself.

While I utilize an alternating current, I do not utilize only small fractions or the crests of the current waves, though such may be used, but I preferably employ substantially all of each current wave, in a single 100 phase system, and do not suppress the current waves of one sign. And with a polyphase alternating current I do not utilize a small fraction only of a current wave, though such may be used, but I employ all the waves 105 of both signs, and preferably utilize that fraction of each half wave, symmetrically on either side of the maximum voltage, which is found by dividing two by the number of phases in the alternating current supply. 110 Thus, in a three phase system, I use two-thirds of each half wave. And, in any case, I do not employ an air gap or a varying resistance, but by the contacting devices shown and described, without any sparking, 115 or variation in resistance, I bring the X-ray tube into perfectly definite electrical connection with the wave source at a definite time.

I do not herein specifically claim subject 120 matter of Fig. 2, but claim the same in my divisional application Serial Number 141,072, filed January 8, 1917:

What I claim is:

1. The combination with a source of high 125 potential alternating current, of an X-ray tube, synchronous switching means for rectifying the current delivered to said tube and

- for connecting said tube with said source comprising relatively movable contacts coming successively into engagement with each other, a resistance periodically bridging 5 neighboring contacts, said resistance affording continuous uninterrupted connection between said tube and said source of current, whereby fluctuation in the energy delivered to said tube is reduced.
- 10 2. The combination with a source of high potential alternating current, of an X-ray tube, of a synchronous rectifying switch comprising relatively movable brushes and contacts, a brush comprising separated contacts and a resistance connecting said separated contacts, said separated brush contacts simultaneously periodically engaging neighboring switch contacts, said resistance, 15 brushes and contacts forming a continuous uninterrupted connection between said source of current and said X-ray tube, whereby fluctuation in the energy delivered to said tube is reduced.
- 15 3. The combination with windings delivering high potential polyphase current, of a consumption circuit, a synchronous rectifying switch intervening between said windings and said consumption circuit, said rectifying switch comprising relatively movable contacts and brushes coming into engagement with each other, and means for introducing resistance between successive phase windings as a terminal of said consumption 20 circuit is transferred from one to another of said phase windings, a terminal of said consumption circuit having continuous uninterrupted connection with said windings through said contacts, brushes and resistance.
- 25 4. The combination with a plurality of windings delivering high potential polyphase current, an X-ray tube, and a high potential rectifying switch connected to said windings and to said X-ray tube and delivering to said X-ray tube uninterrupted 25 current in one direction only, said switch having relatively movable contacts coming into engagement with each other maintaining continuous connection between said X-ray tube and said windings through a path of unvarying resistance, whereby for a given 30 mean of energy delivered to said tube the maximum thereof and resultant destructive effect upon said tube and variations in the rays are reduced.
- 35 5. The combination with a plurality of stationary windings delivering high potential polyphase current, of an X-ray tube, and a high potential rectifying switch passing through said X-ray tube in one direction only uninterrupted current from all the half waves of said polyphase current, said switch having relatively movable contacts coming into engagement with each other maintaining 40 continuous connection between said X-ray tube and said windings through a path of unvarying resistance.
5. The combination with a stationary winding delivering high potential alternating current, of a consumption circuit, a high potential translating device in said circuit, 55 switching mechanism connecting said winding with said circuit, conducting arcs and brushes coming into engagement with said arcs, said brushes comprising contacts having different angular relations with said arcs, a conductor of high resistance connecting said brush contacts, and a circuit connection to said conductor.
6. The combination with a plurality of windings delivering high potential polyphase current, of a high potential rectifying switch comprising relatively moving and engaging sets of contacts, an X-ray tube traversed always in the same direction by energy delivered by said windings through said contacts, the resistance of the path through and between said sets of contacts remaining substantially constant for all relative positions of said contacts.
7. The combination with a plurality of windings delivering high potential polyphase current, of a high potential rectifying switch comprising relatively moving and engaging sets of contacts, an X-ray tube traversed always in the same direction by energy delivered by said windings through said contacts, the resistance of the path through and between said sets of contacts remaining substantially constant for all relative positions of said contacts.
8. The combination with stationary windings delivering high potential polyphase current, of an X-ray tube, a high potential switch intervening between said windings and said tube and comprising relatively rotatable contacts and brushes engaging each other, said brushes comprising contacts so spaced that one of said brush contacts makes connection with one of said first named contacts at substantially the same instant another of said brush contacts makes connection with the next succeeding of said first named contacts.
9. The combination with a source of high potential fluctuating current, of an X-ray tube, a rectifying switch intervening between said source and said X-ray tube for delivering high potential current through said X-ray tube in one direction only, said rectifying switch comprising conducting arcs or segments and coöperating brushes, the brushes comprising contacts engaging and having different angular relations with said arcs or segments, a resistance connecting said contacts together, and a connection from a point intermediate the ends of said resistance to said X-ray tube.
10. A high potential rectifying switch comprising conducting arcs or segments and coöperating brushes, the brushes comprising contacts engaging and having different angular relations with said arcs or segments, a symmetrically acting resistance connecting said contacts together, an X-ray tube having its terminals connected to said resistances, and a source of polyphase high potential current delivering energy always in the same direction through said tube through said rectifying switch, said X-ray tube con-

tinuously connected through said resistances, contacts and arcs or segments with said source through a path of unvarying resistance.

- 5 11. A system of X-ray tube excitation comprising a source of high potential poly-phase current, an X-ray tube, switching mechanism operating in synchronism with said current delivering uninterrupted uni-directional current to said tube, said switching mechanism comprising relatively movable segments and brushes engaging each other and maintaining continuous uninterrupted connection between said X-ray tube 10 and said source of current through solid conductors, whereby resistance pulsations in the circuit of said tube external to said tube are prevented.

- 20 12. A system of X-ray tube excitation comprising a source of high potential poly-phase current, an X-ray tube, synchronous switching mechanism delivering uni-directional uninterrupted current from said source to said tube, said switching mechanism comprising relatively rotating segments and brushes engaging each other, said brushes comprising separated contacts, a resistance having its terminals connected to said contacts, and a circuit connection to said 25 resistance between its terminals, whereby said tube is maintained in definite conductive connection with said source through said switch and short circuiting between phases is prevented.

- 30 13. The combination with a generator of alternating current, of a transformer for stepping said current up to high potential, an X-ray tube, a rectifying switch whose rotatable member is mechanically connected 35 with the rotating element of said generator, said rectifying switch comprising relatively movable contacts and brushes, a brush comprising separated contacts and a resistance connecting said separated contacts, said separated brush contacts simultaneously periodically engaging neighboring switch contacts, said resistance, brushes and contacts forming a continuous uninterrupted connection between said source of current and said 40 X-ray tube, whereby fluctuation in the energy delivered to said tube is reduced.

- 45 14. The combination with a generator of polyphase alternating current, of means for transforming said current to high potential polyphase current, an X-ray tube, a high potential polyphase rectifying switch whose rotatable member is mechanically connected with the rotating member of said generator, said rectifying switch comprising relatively 50 movable brushes and contacts, a brush comprising separated contacts and a resistance connecting said separated contacts, said separated brush contacts simultaneously periodically engaging neighboring switch contacts, and a medium having greater dielectric strength than that of air submerging 55 said brush and switch contacts, said resistance, brushes and contacts forming a continuous uninterrupted connection be-

65 tacts, said resistance, brushes and contacts forming a continuous uninterrupted connection between said source of current and said X-ray tube, whereby fluctuation in the energy delivered to said tube is reduced and short circuiting between different phases is 70 prevented.

75 15. The combination with a generator of alternating current, of a transformer for stepping said current up to high potential, an X-ray tube, a rectifying switch whose rotatable member is mechanically connected with the rotating element of said generator, said generator producing a plurality of electrical cycles for each revolution of the rotatable member of said switch, said rectifying switch comprising relatively movable contacts and brushes, a brush comprising separated contacts and a resistance connecting said separated contacts, said separated brush contacts simultaneously periodically engaging neighboring switch contacts, said resistance, brushes and contacts forming a continuous uninterrupted connection between 80 said source of current and said X-ray tube, whereby fluctuation in the energy delivered to said tube is reduced.

85 16. The combination with a generator of polyphase alternating current, of means for transforming said current to high potential polyphase current, an X-ray tube, a high potential polyphase rectifying switch whose rotatable member is mechanically connected with the rotating member of said generator, said generator producing a plurality of electrical cycles for each revolution of the 90 rotatable member of said switch, said rectifying switch comprising relatively movable brushes and contacts, a brush comprising separated contacts and a resistance connecting said separated contacts, said separated brush contacts simultaneously periodically engaging neighboring switch contacts, said resistance, brushes and contacts forming a continuous uninterrupted connection between said source of current and said X-ray tube, whereby fluctuation in the energy delivered to said tube is reduced.

95 17. The combination with a source of high potential alternating current, of an X-ray tube, of a synchronous rectifying switch comprising relatively movable brushes and contacts, a brush comprising separated contacts and a resistance connecting said separated contacts, said separated brush contacts simultaneously periodically engaging neighboring switch contacts, and a medium having greater dielectric strength than that of air submerging 100 said brush and switch contacts, said resistance, brushes and contacts forming a continuous uninterrupted connection be-

115

120

125

tween said source of current and said X-ray tube, whereby fluctuation in the energy delivered to said tube is reduced.

18. The combination with a source of high potential fluctuating current, of an X-ray tube, means for connecting said tube with said source and for rectifying the current delivered to said tube comprising relatively movable contacts coming successively into engagement with each other, a mass of material having greater dielectric strength than air in which said movable contacts are inclosed, and current restraining means coöperating with said contacts affording continuous uninterrupted connection between said tube and said source of current, whereby fluctuation in the energy delivered to said tube is reduced.
19. The combination with a source of high potential fluctuating current, of an X-ray tube, synchronous switching means for rectifying the current delivered to said tube and for continuously connecting said tube with said source comprising relatively movable contacts coming successively into engagement with each other, a mass of material having higher dielectric strength than air in which said contacts are submerged, a resistance periodically bridging neighboring contacts, said resistance affording continuous uninterrupted connection between said tube and said source of current, whereby fluctuation in the energy delivered to said tube is reduced.
20. The combination with a source of current, of a transformer having small magnetic leakage delivering current at high

potential, an X-ray tube, means for connecting said X-ray tube with said transformer and for rectifying the current delivered thereby to said tube comprising relatively movable contacts coming successively into engagement with each other, and current restraining means coöperating with said contacts affording continuous uninterrupted connection between said tube and said transformer, whereby fluctuation in the energy delivered to said tube is reduced.

21. The combination with a source of current, of a transformer having small magnetic leakage delivering current at high potential, an X-ray tube, means for connecting said X-ray tube with said transformer and for rectifying the current delivered thereby to said tube comprising relatively movable contacts coming successively into engagement with each other, and current restraining means coöperating with said contacts affording continuous uninterrupted connection between said tube and said transformer, whereby fluctuation in the energy delivered to said tube is reduced.

In testimony whereof I have hereunto affixed my signature in the presence of the two subscribing witnesses.
